DESIGN FOR A CARPET SWEEPER

Richard Charles Kadow, Newark, N. J.

Application July 1, 1935, Serial No. 57,474

Term of patent 7 years

To all whom it may concern:

Be it known that I, Richard Charles Kadow, a citizen of the United States and a resident of Newark, in the county of Essex and State of New Jersey, have invented a new, original, and ornamental Design for Carpet Sweepers, of which the following is a specification, reference being had to the accompanying drawing, forming part thereof.

I claim:

The ornamental design for a carpet sweeper as shown and described.

RICHARD CHARLES KADOW.
